Application May 17, 1943, Serial No. 487,372

14 Claims. (Cl. 171—209)

1

This invention relates to ignition means for internal combustion engines and more particularly to apparatus adapted for generating and distributing electrical current.

One of the objects of the present invention is to provide a novel magneto-distributor unit adapted for use in the ignition system of an internal combustion engine wherein the current is generated and distributed at a relatively low voltage.

Another object of the invention is to provide apparatus of the above character wherein the current generating and distributing portions are operatively associated with each other in a novel manner to facilitate construction, assembly, inspection and repair.

Still another object is to provide a novel magneto-distributor for an ignition system embodying a novel source of booster current for facilitating the starting of an engine.

A further object is to provide novel distributor means for low tension electrical current in the ignition system of an internal combustion engine.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being primarily had to the appended claims.

In the drawings, wherein like reference characters refer to like parts throughout the several views,

Fig. 1 is a side elevation, partly in section and with parts broken away, showing one form of magneto-distributor unit embodying the features of the present invention;

Fig. 2 is a top view, with parts broken away and partly in section, of said magneto-distributor unit;

Fig. 3 is an end view of said unit, with parts thereof in section, the section being taken substantially on line 3—3 of Fig. 1;

Fig. 4 is a detail view, partly in section and with parts broken away, the view being taken substantially on line 4—4 of Fig. 1;

Fig. 5 is a diagrammatic view of an ignition system wherein a unit of the character illustrated in Figs. 1 to 4 may be employed; and,

Fig. 6 is a detail diagrammatic view showing a modified form of distributor contact which may be used.

2

A single embodiment of the invention is illustrated in the drawings, by way of example, in the form of a combined magneto-generator and distributor for use in the ignition system of a 9-cylinder engine whereby current is generated and distributed at a relatively low voltage to transformer coils located near and operatively connected to the spark plugs of the engine. In the form shown, the novel magneto-distributor unit is housed in a casing comprising a main casing member 10 of U shaped section and a cover 11 therefor secured in position by screws 12 or other suitable means. The open ends of casing member 10 are closed by suitable end plates 13 and 14 secured in position by any suitable means, such as set screws 13a and 14a, respectively. End plate 13 has a plurality of slotted ears 15 (Fig. 3) formed integrally therewith whereby the entire unit may be operatively secured to an engine for angular adjustment in a manner well understood in the art.

The current generating means embodied in the apparatus of the present invention may be constituted by any of several suitable designs and, in the form shown, comprises a 4-pole magnetic rotor 16 which includes a permanent magnet 17 and pole shoes 18, 18 carried by a shaft 20. The latter is journaled in a suitable bearing mounted in end plate 13 and a roller bearing 21 mounted in a partition 22 formed integrally with casing member 10. The outer end of rotor shaft 20 has a pinion 23 thereon adapted to mesh with a member of the engine for driving the rotor. The other or inner end of shaft 20 has a gear 24 mounted thereon for rotation therewith, the purpose of which will hereinafter appear.

Rotor 16 cooperates during its rotation with a pair of laminated stator poles 25 in a manner well understood in the art to generate electrical current in the winding of a coil 26 wound on a laminated metal core 27. The ends of core 27 are secured to the upper ends of stator poles 25, which are preferably cast into the walls of casing member 10 and are thus firmly held in position. A keeper 28 of laminated metal may also be cast into the lower wall of casing member 10 for magnetically joining the two inactive poles of the rotor while the other poles are cooperating with stator poles 25, 25.

Novel current distributing and circuit breaker means are provided by the present invention and said means are associated with the current generating means above described in a novel manner whereby the parts may be readily and easily constructed and assembled in such a manner as to

make the same readily available for inspection or repair without disconnecting internal electrical leads. In the form illustrated, the distributor and circuit breaker parts are wholly supported in operative relation with rotor 20 by casing cover 11 so as to be bodily removable from main casing member 10. Cover 11 has a pair of spaced depending brackets or bearing supports 29 and 30 which are formed integrally with or are otherwise suitably secured to said cover. These supports are 10 provided with suitable low friction bearings 31 and 32 for rotatably supporting a hollow distributor shaft 33.

The inner end of shaft 33 has a gear 34 mounted thereon which is adapted to mesh with gear 24 when cover 11 is secured in position. Gear 34 is preferably drivably connected to shaft 33 by adjustable coupling means 35 for timing purposes, i. e., for effecting small angular adjustments of shaft 33 relative to rotor shaft 20. Said 20 coupling means, as illustrated in the drawings, comprises a set of ratchet teeth on the hub of gear 34, an oppositely facing set of ratchet teeth on an annular shoulder formed on shaft 33, one of said sets having one less teeth than the other set, and an intermediate ring loosely mounted on the shaft with ratchet teeth on both faces thereof for meshing with the first-named sets of teeth. The two sets of ratchet teeth are so formed that one set provides a positive drive in one direction while the other set provides a positive drive in the other direction. Since the above-described coupling means is old per se, the same being shown in Spengler U. S. Patent No. 2,266,283, it is believed to be unnecessary to illustrate and describe the same in more detail. The ratchet teeth of the coupling 35 are normally held in mesh for drivably connecting shaft 33 and gear 34 by means of a bolt 36 which extends through hollow shaft 33 and has a head 37 adapted to engage the outer face of gear 34. Shaft 33 and head 37 of the bolt have interlocking portions to hold the same against relative angular movement. The other end of bolt 36 is externally threaded for receiving a nut 38 which serves to hold the shaft and gear assembly in assembled relation. When nut 38 is loosened sufficiently, the ratchet teeth of coupling 35 are yieldably held in engagement by a coil spring 39 so that an angular adjustment of shaft 33 relative to gear 34 and, hence, rotor shaft 20, may be made in a manner well understood in the art and fully described in Spengler U. S. Patent No. 2,266,283. Since the adjustable coupling means per se do not constitute a part of the present invention, it is not believed that a further detail description of the structure and operation thereof is necessary.

Novel means are provided in association with shaft 33 for distributing low voltage current generated in coil 26, said means being mounted between brackets 29 and 30 and comprising a rotating finger 40 keyed on the central portion of shaft 33 and a stationary contact carrying block 41 fixed to bracket 30 by any suitable means, such as screws 42. Finger 40, as shown, comprises a molded block 43 of insulating material having a current pick-up brush 44 and a distributing brush 45 mounted thereon in a novel manner. Block 43 has two axially-extending, radially-spaced passages for slidably receiving said brushes, which may be made of carbon or other suitable conducting material. Molded into block 43 and extending across said passages near one face of finger 40 is a metallic conducting strip 46. The latter has openings which coincide with

the above-mentioned passages in block 43 for receiving wire conductors 47 that are suitably attached and electrically connected to brushes 44 and 45. The attachment of wires 47 to the brushes may be effected by molding the ends of the wires in the brushes during manufacture of the latter. Flexible wire conductors 47 are secured, such as by means of solder, to strip 46, thereby electrically connecting the two brushes 44 and 45 to each other. For a purpose to appear hereafter, said brushes are yieldably pressed outwardly by coil springs 48 interposed between the ends of the brushes and insert 46. The outward movement of the brushes is limited by the extended length of wires 47. The parts of the distributor means are accessible for inspection and repair through openings in the sides of casing member 10, said openings being covered by removable plates 10'.

Brushes 44 and 45 of rotatable finger 40 engage a contact ring 49 and a plurality of circularly arranged arcute contacts 50, respectively, which constitute parts of the stationary distributor member 41. Said ring and contacts are preferably molded in the face of a block 51 of insulating material and are connected to terminals 52 and 53, respectively, which extend through block 51 to the opposite face thereof. A single supply terminal 52 is connected to ring 49 for the attachment of a lead from one or more sources of electrical current, whereas each of the contacts 50 has a terminal 53 for connection with an outgoing cable 54. Current thus passes from the source, such as coil 26, through ring 49 to brush 44 and thence through conductors 47, 46, 47 and brush 45 to one of the contacts 50 which is operatively connected with a transformer to supply energy to a spark plug of the engine in a manner to be hereinafter described.

In the construction of distributor block 41, two concentric rings are embedded in the face of the molded insulator 51. One of these rings is thereafter cut, such as by means of a circular saw, along radial lines, as shown in Fig. 4, to divide the same into a plurality of segmental contacts 50, one for each cylinder of the engine. These contacts are preferably connected through terminals 53 and leads 54 to the terminals in the socket portion 55 of a detachable connector, such as a "Cannon" plug. The connecting leads 56 from the plug portion 56a (Fig. 5) of the detachable connector may extend through a suitable radio-shielding harness to the spark plugs 57 of the engine, that is, to the primary windings 58 of individual transformers 59 which have the secondary windings 60 thereof connected to the spark plugs in the case of a low tension distribution system.

On the end of shaft 33 adjacent end plate 14, 60 there is provided a circuit breaker cam 61 which is of the so-called compensated type when the apparatus is used on radial engines wherein properly timed sparks do not occur at equal intervals, in which event the distributor contacts 50 are 65 preferably of unequal lengths for purposes of compensation also. The cam, as shown, has a lobe for each cylinder of the engine and is adapted to operate a main circuit breaker 62 (Fig. 3) which is adjustably mounted on the face of bracket 30 opposite distributor block 41, whereby the same may be readily inspected or adjusted by removing end plate 14. This circuit breaker may be of any suitable known construction, the one illustrated being of the type shown in Shoemaker 70 et al. Patent No. 1,866,492 and hence a detailed

description thereof is believed to be unnecessary.

Circuit breaker 62 has one terminal or contact thereof grounded through the casing 10 and the other terminal or contact connected to terminal 52 of distributor ring 49 by lead 63, and to one terminal of a condenser 64 by means of a lead 65. Condenser 64, which has the other terminal thereof grounded and thus connected across the contacts of circuit breaker 62, is preferably supported in the hollow of cover 11 by means of a bracket 67 that is in turn removably secured to said cover by screws 68. Terminal 52 is also connected by a lead 66 to the output side of coil 26, thereby connecting said coil to the ungrounded side of circuit breaker 62.

For the purpose of rendering the apparatus inoperative, i. e., incapable of furnishing electrical energy to the spark plugs, the normally ungrounded end of coil 26 may be connected to ground through a suitable ignition switch 69 (Fig. 5). In the embodiment shown, a ground connection is made through a lead 70 connected to terminal 52, a detachable plug-in connector 71 (Fig. 2) and a lead 72 to ignition switch 69. The socket portion of said plug-in connector is preferably removably mounted in cover 11 and the plug portion of the connector is removably secured to said socket portion, as illustrated in Fig. 2.

In the operation of the apparatus thus far described, rotor 16 is driven by the engine through splined member 23 to induce alternating currents in coil 26. When the contacts of circuit breaker 62 are in closed position, this current flows along the path of least resistance, i. e., across said contacts to ground. Each time the current in coil 26 approaches its peak value, the contacts of circuit breaker 62 are opened by cam 61, whereupon a surge of current flows through terminal 52 to distributor ring 49 and thence through brushes 44 and 45, a distributor contact 50, a lead 54, 56 and the primary winding 58 of an ignition coil 59. This sudden rise or surge of current in said primary winding causes a high tension current to be induced in the secondary winding 60 of the ignition coil and hence creates a spark across the gap of a spark plug 57. The apparatus is so designed that this operation is repeated each time brush 45 moves from one contact 50 to another, thereby causing the spark plugs of all the engine cylinders to fire in a predetermined sequence, the timing of the sparks being determined by the periodic opening of circuit breaker 62 as effected by cam 61.

Means are also provided for supplying a sufficiently strong current to the spark plugs for firing the same when the magneto rotor is rotated too slowly for this purpose, as when the engine is being started. The starting or booster current is supplied from an outside source, such as a battery 73 (Fig. 5) and is distributed to the ignition coils and the spark plugs through the same distributor parts as the main operating current from coil 26. The proper timing of the delivery of the booster energy to the spark plugs is preferably effected by a second circuit breaker 74, which is similar in construction to circuit breaker 62 and is operated by cam 61. The booster circuit breaker is mounted on but insulated from bracket 30 and, hence, from ground, one terminal or contact thereof being connected with the source of booster current through a lead 75 and a plug-in connector 76 mounted in cover 11 and similar to or identical in construction with connector 71. The other terminal or contact of insulated circuit

breaker 74 is connected by a suitable lead 77 to ring 49 of the distributor mechanism.

In the embodiment illustrated in Fig. 5, the booster or starting current is supplied by battery 73 through a buzzer type interrupter 78 which comprises a solenoid coil 79 and a buzzer or circuit breaker 80. The latter is normally held in closed position by resilient means 81 and is adapted to be electromagnetically opened by solenoid 79 when the latter is energized. One end of the coil of solenoid 79 is connected to a terminal of circuit breaker 80 and the other end thereof is adapted to be connected to ground through ignition switch 69 when the latter is in "on" position, as illustrated. The end of coil 79, which is connected to circuit breaker 80, is also connected through a resistance 82 to circuit breaker 74 through plug-in connector 76 and lead 75. A suitable condenser 83 is connected across the contacts of circuit breaker 80 to eliminate arcing and a current limiting fuse 84 is preferably provided for limiting the current in the event the contacts of circuit breaker 80 should stick in closed position. A starter operated switch 85, which may be adapted to open automatically upon starting of the engine, is also provided in the circuit between battery 73 and interrupter 78.

When it is desired to start the engine, switch 85 is closed and ignition switch 69 is moved to the illustrated "on" position. Current from battery 73 then flows through circuit breaker 80 and solenoid coil 79 to ground at switch 69. Upon energization or excitation of solenoid 79, circuit breaker 80 is electromagnetically opened, thereby cutting off the flow of current from battery 73. This results in the deenergization of solenoid 79 so that spring 81 is effective to again close the circuit at circuit breaker 80. This cycle is repeated in rapid succession as long as switches 69 and 85 are in the positions mentioned above.

Each time circuit breaker 80 is opened, the magnetic field built up around coil 79 by the current flowing therethrough from battery 73 collapses and induces a relatively high voltage across the coil, thereby causing a sudden rise of current which will flow through a circuit including resistance 82 and circuit breaker 74, provided the contacts of the latter are in closed position. If the contacts of circuit breaker 74 are in closed position and circuit breaker 62 is open, the energy stored in the magnetic field of booster coil or inductance 79 is thus released in a surge to the magneto primary circuit each time contacts 80 open and is distributed to transformer coils 59 in the same manner as the main operating current heretofore described. The surges of energy delivered to primary windings 58 in this manner induce a current in the secondary windings which are capable of causing the desired sparks at gaps 57. The timing of the initial booster spark at each spark plug is thus determined by the closing of booster breaker 74 during the operation of interrupter 78 while circuit breaker 62 is in open position. The booster circuit and the operation thereof are more fully described and claimed in an application of Marc C. Sawyer for "Ignition means," filed on or about May 12, 1943.

Resistance 82 is provided in the circuit for the dual purpose of preventing a dead short circuit when both circuit breakers 62 and 74 are in closed position and to limit the maximum current which might flow through generator coil 26 from the booster circuit if the points of vibrator 80 should stick in closed position. This current through coil 26 must be sufficiently small to avoid undue

demagnetization of rotor magnet 17. In one satisfactory embodiment of the invention, resistance 82 has a value of approximately 3 ohms, the resistance of coil 79 is approximately one ohm, and the resistance of each primary winding 58 is approximately 16 ohms. The relatively high resistance of windings 58 is desirable for the purpose of quickly dissipating the residual energy therein after the firing of each spark plug. The quick dissipation of the residual energy in the primary circuit after the firing of each spark plug is desirable for the purpose of avoiding arcing in the distributor as brush 45 passes from one contact 50 to another and to avoid the production of secondary sparks at the plugs at the same time.

In Fig. 6, there is illustrated a modified form of contact for use in the distributor shown in Figs. 1 to 4 in lieu of contacts 50. Each of the distributor contacts 50 may be divided into a plurality of separate sections or segments, three such sections 50a, 50b and 50c being shown. Contact segment 50a, which is the first of the three to be contacted by brush 45 during rotation of the distributor finger, is connected to outgoing lead 54 in the same manner as contacts 50. Segments 50b and 50c are connected to said lead through resistance 90 and resistances 90, 91, respectively, said resistances being provided in lieu of incorporating a resistance in the coil windings 58, as mentioned above. Thus, when the current is permitted to flow from the source to coil 59 upon the opening of circuit breaker 62, there is but little resistance in the primary circuit. However, after the desired spark has occurred as a result of the first surge of current, brush 45 moves on to segments 50b and 50c in succession, thereby successively inserting resistances 90 and 91 in the primary circuit for the purpose of dissipating any residual energy therein before said brush moves on to the next distributor contact. The residual energy in the primary circuit is thus gradually dissipated by resistances which do not interfere with the production of the essential spark at the spark plugs.

There is thus provided a novel magneto-distributor unit adapted for use in the ignition system of an internal combustion engine wherein distribution of current from a single source to a plurality of spark plugs is accomplished at a relatively low voltage. Additionally, there is provided a unit of the above character which is so constructed as to facilitate assembly thereof and to also facilitate inspection, adjustment and repair of the vital parts thereof. The construction of the unit provided is such that the wiring thereof is simplified and afforded maximum protection when the unit is partially disassembled for inspection or the like.

Although only a single embodiment of the invention has been illustrated and described in detail, it is to be expressly understood that the same is not limited thereto. For example, many variations might be made in the current generating means, that is, the rotor may have a different number of poles than the rotor illustrated, or a generator of the stationary magnet type might be employed. Also, many different types of plug-in connectors may be employed in lieu of those illustrated. Various other changes in the design and arrangement of parts illustrated may also be made, as will now be apparent to those skilled in the art, without departing from the spirit and scope of the invention. For a definition of the

limits of the invention, reference is primarily had to the appended claims.

What is claimed is:

1. In apparatus of the class described, a magneto-generator comprising a rotor, a casing comprising a main casing member and a cover removably secured thereto, means for rotatably mounting said rotor in said main casing member, ignition distributor means and circuit breaker means mounted on and removable with said cover, and means for automatically drivably connecting said rotor and the rotatable parts of said distributor and circuit breaker means whenever said cover is in assembled position on said main casing member.
2. In apparatus of the class described, a magneto-generator comprising a rotor, a casing comprising a main casing member and a cover removably secured thereto, means for rotatably mounting said rotor in said main casing member, ignition distributor means and circuit breaker means mounted on and removable with said cover, a shaft rotatably mounted on said cover for driving the rotatable parts of said distributor and circuit breaker means, and gears on said shaft and rotor adapted to mesh for drivably connecting said shaft and rotor whenever said cover is operatively secured to said main casing member.
3. In apparatus of the class described, a magneto-generator comprising a rotor, a casing comprising a main casing member and a cover removably secured thereto, means for rotatably mounting said rotor in said main casing member, ignition distributor means and circuit breaker means mounted on and removable with said cover, means for automatically drivably connecting said rotor and the rotatable parts of said distributor and circuit breaker means whenever said cover is in assembled position on said main casing member, and sockets of plug-in connectors mounted in said cover and connected to all electrical leads from said distributor and circuit breaker means to be connected to leads externally of said casing.
4. In apparatus of the class described, a magneto-generator comprising a rotor, a casing comprising a main casing member and a cover removably secured thereto, means for rotatably mounting said rotor in said main casing member, ignition distributor means and a pair of circuit breakers mounted on and removable with said cover, means for operatively connecting one of said circuit breakers to the coil of said magneto-generator, means extending through said cover for operatively connecting the other of said circuit breakers to a source of electrical energy outside said casing, means extending through said cover for connecting the output terminals of said distributor means to circuits outside said casing, and means for automatically drivably connecting said rotor and the rotatable parts of said distributor means and said circuit breakers whenever said cover is in assembled position.
5. In apparatus of the class described, a casing comprising a main body member and a cover therefor, electrical current-generating means including a coil and a rotor mounted in said member, an ignition distributor comprising a rotatable member, circuit breaker means including a rotatable cam, said distributor and circuit breaker means being wholly supported by said cover within said casing, and means for drivably connecting said rotatable member and cam to said rotor when said cover and body member are secured together in operative relation.

6. In apparatus of the class described, a casing comprising a main body member and a cover therefor, electrical current-generating means including a coil and a rotor mounted in said member, a shaft rotatably supported by said cover, an ignition distributor supported by said cover and including a rotatable part on said shaft, circuit breaker means supported by said cover and including a cam on said shaft, and means on said shaft and rotor for drivably connecting the same when said cover is in operative position on said body member.

7. In apparatus of the class described, a casing comprising a main body member and a cover therefor, electrical current-generating means including a coil and a rotor mounted in said member, an ignition distributor and circuit breaker means wholly supported by said cover and extending for the most part into said body member, said current-generating means being operatively electrically connected with said distributor and circuit breaker means, and means for drivably connecting said rotor and the rotatable parts of said distributor and circuit breaker means whenever said cover is secured in operative position on said main body member.

8. In apparatus of the class described, a casing comprising a main casing member and a cover removably secured thereto, a magneto-generator including a rotor and coil mounted in said casing member, a shaft rotatably mounted on said cover, ignition distributor means mounted on said cover between the bearings for said shaft and having a rotatable part thereof mounted on said shaft for rotation therewith, circuit breaker means mounted on said cover and including a cam mounted on said shaft adjacent one end thereof, means on the other end of said shaft for drivably connecting the latter to said rotor whenever said cover is secured in position on said casing member, and means for operatively electrically connecting said coil, distributor means and circuit breaker means.

9. In apparatus of the class described, a casing comprising a main casing member and a cover removably secured thereto, a magneto-generator including a rotor and coil mounted in said casing member, a shaft rotatably supported by said cover, ignition distributor means supported by said cover between spaced bearings for said shaft and having a rotatable part thereof mounted on said shaft for rotation therewith, circuit breaker means supported by said cover and including a cam mounted on said shaft adjacent one end thereof, means on the other end of said shaft for drivably connecting the latter to said rotor whenever said cover is secured in position on said casing member, means for operatively electrically connecting said coil, distributor means and circuit breaker means, a removable cover on the side of said casing member for permitting access to said distributor means, and a removable cover on the end of said casing member for permitting access to said circuit breaker means.

10. In apparatus of the class described, a casing comprising a main casing member and a cover removably secured thereto, a magneto-generator including a rotor and coil mounted in said casing member, a hollow shaft rotatably mounted on said cover and removable therewith from said member, ignition distributor means supported by said cover and having a rotatable part mounted on said shaft for rotation therewith, circuit breaker means supported by said cover and comprising a cam mounted on said shaft for rota-

tion therewith, means for operatively electrically connecting said coil, distributor means and circuit breaker means, means for drivably connecting said rotor and shaft whenever said cover is secured in position on said member, said last-named means including a gear on said shaft and means for coupling said gear and shaft for angular adjustments relative to each other, and means including a bolt extending through said hollow shaft for normally holding said coupling means in driving engagement.

11. In apparatus of the class described, a casing having two detachably connected sections, a magneto-generator comprising a rotor and coil mounted in one of said sections, a rotatable shaft mounted in two spaced bearings supported in the other of said sections, an ignition distributor supported by said other section between said bearings and including a rotatable part on said shaft, circuit breaker means supported by said other section and including a cam mounted on said shaft for rotation therewith, means for operatively electrically connecting said coil, distributor and circuit breaker means, and means for drivably connecting said rotor and shaft.

12. In apparatus of the class described, a casing comprising a main body member and a removable cover therefor, electrical current-generating means including a coil and a rotor mounted in said member, circuit breaker means including a rotatable cam wholly supported by said cover within said casing, means for electrically connecting said coil and circuit breaker means, and means drivably connecting said cam to said rotor whenever said cover and body member are secured together in operative relation.

13. In apparatus of the class described, a casing comprising a main body member and a removable cover therefor, electrical current-generating means including a coil and a rotor mounted in said member, an ignition distributor comprising rotatable means and a stationary contact carrying block wholly supported by said cover within said casing, means for electrically connecting said coil and distributor, and means drivably connecting said rotatable means to said rotor whenever said cover and body member are secured together in operative relation.

14. In apparatus of the class described, a casing comprising a main body member and a cover therefor, electrical current-generating means including a coil and a rotor mounted in said member, an ignition distributor comprising rotatable means and a stationary insulating block with contact means thereon wholly supported by said cover within said casing, said contact means comprising an annular contact concentric with the axis of rotation of said rotatable means and a plurality of circularly arranged contacts disposed on a circle concentric with said annular contact and said rotatable means comprising an insulating member having a pair of radially-spaced, axially-extending openings therein, an electrical conductor secured to said insulating member and extending across adjacent ends of said openings, a conducting brush slidably mounted in each of said openings and adapted to project therefrom for rubbing contact with said contact means, resilient means normally under compression in said openings tending to move said brushes away from said conductor and flexible means for electrically connecting said conductor to said brushes and for limiting the movement of the latter by said resilient means, means for electrically connecting said coil to said annular contact,

and means drivably connecting said rotatable means to said rotor whenever said cover and body member are secured together in operative relation.
